(57) **CLAIM**

The ornamental design for a multifunctional hat, as shown and described.

DESCRIPTION

FIG. 1 is a perspective view of a first embodiment of a multifunctional hat showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of portion 9 shown in FIG. 2;

FIG. 10 is a perspective view of a second embodiment of the multifunctional hat;

FIG. 11 is another perspective view thereof;

FIG. 12 is a front elevational view thereof;

FIG. 13 is a rear elevational view thereof;

FIG. 14 is a left side elevational view thereof;

FIG. 15 is a right side elevational view thereof;

FIG. 16 is a top plan view thereof;

FIG. 17 is a bottom plan view thereof;

FIG. 18 is a perspective view of the multifunctional hat where the multifunctional hat is in a configuration of use;

FIG. 19 is an enlarged view of portion 19 shown in FIG. 10;

FIG. 20 is a perspective view of a third embodiment of the multifunctional hat;

FIG. 21 is another perspective view thereof;

FIG. 22 is a front elevational view thereof;

FIG. 23 is a rear elevational view thereof;

FIG. 24 is a left side elevational view thereof;

FIG. 25 is a right side elevational view thereof;

FIG. 26 is a top plan view thereof;

FIG. 27 is a bottom plan view thereof; and,

FIG. 28 is a perspective view of the multifunctional hat where the multifunctional hat is in a configuration of use.

The dash-dash broken lines and the unshaded areas adjacent to those broken lines in the drawings depict portions of the multifunctional hat that forms no part of the claimed design.

(Continued)

The dot-dash broken lines depict boundaries of the enlarged portions and form no part of the claimed design.
